H. D. MEEK

WEATHER STRIP ATTACHMENT

Filed March 12, 1927

Hamilton D. Meek,

E. J. Siggers
and *Philip E. Siggers, Attorneys*

UNITED STATES PATENT OFFICE.

HAMILTON DUNBAR MEEK, OF LOS ANGELES, CALIFORNIA.

WEATHER-STRIP ATTACHMENT.

Application filed March 12, 1927. Serial No. 174,914.

My invention aims to provide an improved weather strip attachment for hinged French windows, shutters and the like.

One of the objects of the invention is to produce a weather strip attachment which is automatically projected into contacting relation with a French window sill upon closing the window, and to provide improved means for operating the same.

Other advantages of my invention will appear in the specification when considered in connection with the accompanying drawing, wherein I have illustrated a preferred form thereof, and in which,

Figure 1 is a fragmentary perspective view of a French window having my improved weather strip attachment secured thereto;

Figure 2 is a fragmentary longitudinal sectional view of the device shown in Figure 1, and showing the weather strip engaging the sill of the window.

Figures 3, 4 and 5 are sectional views taken on the lines 3—3, 4—4 and 5—5, respectively, of Figure 2.

Figure 6 is an end elevation of the device shown in Figure 1.

Referring specifically to the drawings and to the illustrated form of the invention shown therein, I have provided a housing casing 10, preferably of sheet metal, and conveniently made like a long, hollow rectangular box to form a housing for the mechanism and for a weather strip operated thereby, which is adapted to be projected into engaging relation with the window sill or the like. To provide means for securing this casing or housing to the lower portion of the window, I have shown a series of holes for receiving screws, bolts, nails or the like.

Within the housing 10, I provide a flanged sheet metal plate 11 adapted to engage the face of the window and having the flanges at its upper side and at its ends engaging the inner wall of the housing inside the row of holes, thereby providing a stop for the housing 10 when it is secured to the window, and a separate wall to which various pivot pins and the like may be secured.

As best shown in Figures 4 and 5, the lower portion of the housing is open and the weather strip plate 12 is mounted therein so that it may be retracted into and projected from the housing. Herein the plate 12 is shown as being made of sheet metal, although it is understood that suitable felt

or rubber material may be applied to its lower edge if it is so desired.

A part of my invention consists of improved mechanism for projecting and reTRACTING the plate 12 automatically from and into the casing incident to movements of the window or other hinged shutter. To this end, I have shown a flat master lever 13 (see Figure 2) arranged substantially vertically and pivoted to swing about its central portion on a suitable pin, bolt or rivet adapted for the purpose. This lever is shown as connected to lift or project the plate 12 upon movement in one direction or the other, as the case may be. I have shown in the drawings (see Figure 2) a pair of bell crank levers in the form of plates 14 hinged within the housing, and cooperating with suitable projections 15 near the opposite ends of the plate 12, the bell crank plates having slots 16 to permit the necessary swinging movement thereof. Each of the bell crank lever plates is connected by pivoted links 17 to the master lever 13. The distances from the pivotal point of the master lever to the pivotal connection of the links 17 thereon are equal, so that the movement of the bell crank plates will correspond and be in the same direction.

For actuating the mechanism just described, automatically upon closing the window or shutter to which my improved weather strip is attached. I have shown a rod or operating arm 18 (see Figure 2), pivotally connected to the master lever 13 by means of a bent flat strip 18^a having a U-shaped end portion presenting holes through which the rod projects, and a shock absorbing spring 18^b surrounds the rod in the U-shaped end. This prevents overstrain or breakage in case the arm is adjusted to project the shutter too far or the plate strikes an obstruction.

On the end of the rod 18, I have shown an adjustable head 19 arranged to project from that end of the housing where it will engage and be actuated by coming in contact with the window jamb or door casing, as the case may be. Herein, the headed end of the operating arm 18 is screw-threaded thereon, so that it may be adjusted to move the master lever more or less as it is desired to project the plate 12 a greater or less distance from the casing to engage the window sill.

It is now clear that the mechanism just described will function to project the plate

into frictional engagement with a window sill to prevent rain or cold air from entering the house. To retract the plate 12 automatically from engagement with the window sill upon opening movement, I provide a spring 20 which coacts with the master lever 13, and is secured to a stationary part of the casing. I have shown the upper end of the lever 13 as having an offset ear to receive a hooked end of the spring although it may be otherwise engaged, and the upper flange of the plate 11 has an interrupted portion to provide room for the spring to work. As best shown in Figure 2, the upper flange of the inside plate 11 has a series of openings to receive the other hooked end of the spring 20, although it is understood that the spring may be otherwise connected to the casing.

20 From the foregoing description, it will be seen that the securing bolts, screws or the like, are so arranged that they will not interfere with the movement of the plate 12. Moreover, the plate is shown as being so shaped that the pivot pins and bolts for the links and levers will not interfere with its movement when it is fully retracted.

One of the important advantages of my invention is that it can be manufactured very easily and cheaply of heavy sheet metal and practically all of the parts can be stamped out. Furthermore, the attachment to a window or other shutter can be made very easily and quickly by any unskilled laborer. The parts are very simple and can easily be removed for repairs. All of the operating mechanism is protected from the weather by the housing. The operating mechanism, being made almost entirely of sheet metal parts, can be housed in a very small space.

Having thus described the preferred embodiment of my invention without limiting myself thereto, what I claim and desire to secure by Letters Patent is:

45 1. A weather strip attachment of the class described comprising, in combination, a sheet metal housing having provision to be secured to the lower portion of a shutter, said housing having an open lower portion, a strip within the housing arranged to be projected therefrom, and retracted therein, a pair of bell cranks near both ends cooperating with the strip to actuate it, a centrally arranged and pivotally mounted master lever connected to actuate said bell

cranks, spring means normally holding said master lever in position to retract the strip, and an adjustable actuating arm projecting from one end of the casing and arranged to engage the shutter casing upon final closing movement thereof to project said strip into engagement with the sill. 60

2. A weather strip attachment for shutters comprising, in combination, a housing secured to the lower end of the shutter, said housing having an open lower wall, a strip mounted within the housing and adapted to be projected therefrom to engage the sill, a pair of bell cranks mounted within the housing and connected to actuate said strip, a master lever pivotally mounted within the housing between the bell cranks, links connecting the master lever to the bell cranks, a coil spring connected to the master lever to maintain the strip in retracted position, an operating arm for the master lever projecting from the said housing adjacent to the hinged edge of the shutter and arranged to engage the shutter casing upon final closing movement thereof to project the strip into engagement with the sill. 70

3. A weather strip attachment for window shutters and the like, comprising, in combination, a plate arranged to be projected against the window sill, operating means including a reciprocable arm connected to said plate and arranged to be actuated incident to the final closing movement of the window, and a shock absorbing spring operatively interposed in said operating arm to prevent breakage of the parts of the operating mechanism. 80

4. A weather strip attachment for shutters comprising, in combination, a sheet metal casing; a plate slidably mounted within the casing, a pair of sheet metal bell cranks pivoted in the casing and connected to the plate; each bell crank having an elongated slot where it is connected to the plate to permit pivotal movement; a master lever for the bell cranks; links connecting the master lever and the bell cranks; an operating arm projecting through one end wall of the casing and connected to the master lever; a cushion spring in the arm; and a spring to return the parts to retracted position. 90

In testimony, that I claim the foregoing as my own, I have hereto affixed my signature.

HAMILTON DUNBAR MEEK.
